esse. Granton.

Follows Patent.

The subject referred to in this Follows Patent and making part of the same containing a description in the words of the said Esse Grantron himself of his improvement in the Prop.

Construct a frame & iron scroll somewhat similar to other frames for presses, having uprights with a bar piece and two or four cap pieces strongly joined together, between the cap pieces is the shaft to which the cams are attached, the shaft operates the frame with the cap pieces & the shaft is to contain either two or four cams, when the shaft contains but two cams, they are placed near the center of the shaft on each side a double rock which is attached to the follower, in the center when the shaft contains four cams they are placed near each end of the shaft to operate a double rock, these on each end of the follower, the cams are raised on the shaft on opposite sides so that when one cam is up the other is down, so when the cams are down, to accomplish continued motion there are sliding blocks with pins then rolling; connected with these blocks are double hinged springs, with weights to draw them into the rocks which continue the pressure downward, these blocks are to be raised ultimately by slopes of iron or iron other metal passing over the cams on the shaft.

The prop contains either two or four double rocks which are placed either in the center of the prop or in each end of the follower, the follower contains either two or four friction rollers also the rocks if expedient.

The prop operates either with a wheel or lever attached to the iron shaft either at one or both ends, the follower and rocks are drawn up by a iron chain or slope attached to the shaft, the spurs are to be released either by a hinge or a slide hatched placed on the inner sides of the cap.

The parts I claim as my invention are those which cause the continued pressure, which is the application of the rocks and sliding blocks to the
